UNITED STATES PATENT OFFICE.

WILLIAM WRIGHT CLIMENSON, OF HONEY BROOK, PENNSYLVANIA.

NECKTIE-SPICE.

1,281,766.

Specification of Letters Patent. Patented Oct. 15, 1918.

Application filed August 14, 1917. Serial No. 186,132.

To all whom it may concern:

Be it known that I, Dr. WILLIAM W. CLIMENSON, a citizen of the United States, residing at Honey Brook, in the county of

5 Chester and State of Pennsylvania, have invented a new and useful Necktie-Splice, of which the following is a specification.

The device forming the subject matter of this application is a splice adapted to be 10 placed in the rear portion of a necktie, to the end that the tie may slide readily between the parts of a double walled collar, and in order that the novel features of the present invention may be clearly understood, it is desirable to explain, at some 15 length, the working of a device of this kind, to allude to the problems presented in the process of manufacture, and to comment at some length on the prior art.

20 If a necktie splice of the kind disclosed is to permit the tie to slide longitudinally between the walls of a collar, the splice must embody a pair of strips between which the button at the rear of the collar is received, 25 since, if the rear end of the button bears against the splice, the splice is pressed against the outer wall of the collar, and the friction thus produced interferes with the free longitudinal sliding movement of the 30 tie. A necktie splice made up of two parallel strips, between which the rear button is received, is shown in the British patent to Foster, No. 6429 of 1892, but a splice which consists merely of two parallel strips, 35 having their ends sewed directly into the tie, will not operate successfully, as I have found by experiment, for reasons hereinbefore set forth; nor is it possible to sell, as an article of manufacture, a tie splice which 40 consists of two free strips adapted to be sewed into a tie, and having no connecting means which permanently and firmly engage the ends of the strips.

45 It has been found as a matter of test and experiment, that when the ends of the strips are sewed into the tie directly, it is practically impossible to make the strips of the same length. If the strips are not of the same length, one of two results is produced. 50 First, the tie, when laid out flat, is in the form of an obtuse angle and, when the tie is tied, that portion of the tie which forms the knot, is either too high or too low at the front of the collar; or, secondly, one of the 55 strips of the splice at the rear of the collar is tight and the other of the strips of the

splice is loose, the loose strip of the splice becoming detached from the rear collar button, rolling up, and otherwise interfering with the proper sliding of the tie between the walls of the collar. 60

Further, when the ends of the strips of the splice are sewed directly into the tie, without the employment of rigid transverse connections between the ends of the strips 65 of the splice, the splice and the terminal portions of the tie, at the ends of the splice, soon become rolled up into a cord-like or cylindrical form of considerable diameter, which interferes with the proper sliding of 70 the tie.

In view of the foregoing, it is the object of the present invention to provide, in a necktie splice embodying a pair of longitudinal strips, rigid transverse reinforcements which engage and grip the ends of the strips of the splice. I am aware that, 75 as shown in the British patent to Rosenberger, No. 6052 of 1910, it has been proposed to assemble a splice slidably and adjustably with a pair of terminal members, but, so far as I am advised as to the state of the art, including such patents as the United States patent to Schlesinger 326251, the British patent to Schmidt 18157 of 1911, 80 and the British patent to Haworth 10270 of 1910, no one heretofore has permanently and securely attached, without sewing, to the ends of a pair of strips, in a necktie splice, a pair of rigid transverse reinforcements, 85 to produce the results above mentioned, and to obviate the difficulties hereinbefore pointed out.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention. 95

In the accompanying drawings:—

Figure 1 shows in rear elevation, a portion 105 of a tie whereunto the device forming the subject matter of this application has been applied, parts being broken away;

Fig. 2 is an elevation showing the splice, 110 parts being broken away;

Fig. 3 is a fragmental elevation showing a part of one of the reinforcements;

Fig. 4 is a section on the line 4—4 of Fig. 2.

The necktie splice forming the subject matter of this application includes a body member denoted by the numeral 1 and comprising a pair of parallel strips 2, disposed edge to edge. The strips 2 preferably are inelastic, and are made of some material which will produce but little friction when 10 in contact with the walls of a collar.

The invention comprises a pair of relatively rigid reinforcements 3, made of metal. The reinforcements 3 are of U-shape in cross section and include walls 4. Burs 5 are punched from the walls 4, the burs 5 preferably being of triangular form and including a straight edge 6 disposed transversely to the length of the strips 2. The outer corners of the reinforcements 3 are beveled 20 as shown at 7, for a purpose which will be described hereinafter.

The numeral 8 denotes a tie, the rear ends of which are indicated by the reference character 9, and are of tubular form.

25 In practical operation, the ends of the strips 2 of the body member 1 are placed between the walls 4 of the reinforcements 3, the walls of the respective reinforcements being clamped on the ends of the strips, and 30 the projections or burs 5 engaging the ends of the strips. From the foregoing, it will be observed that, by a simple operation, and without sewing, the reinforcements 3 may be connected with the ends of the strips 2, 35 the tie splice then constituting an article of manufacture which may be sold independently of the tie. Since the burs 5 include the straight edges 6 arranged at right angles to the length of the strips 2, the burs are 40 well adapted to withstand the longitudinal pull imparted to the splice when the tie is slid endwise between the walls of a collar.

The reinforcements 3 are inserted into the tubular ends of a tie 8, and in this connection it is to be observed that the beveling indicated at 7 facilitates the insertion of the reinforcements into the ends of the tie.

Copies of this patent may be obtained for five cents each, by addressing the "Commissioner of Patents, Washington, D. C."

Further, after the reinforcements 3 are mounted in the ends 9 of the tie, the corners of the reinforcements will not be likely to 50 wear their way through the ends of the tie, since these corners are beveled off as shown at 7. The reinforcements 3 are sewed as shown at 10, into the ends 9 of the tie and, if desired, longitudinal U-shaped stitchings 55 11 in the ends 9 of the tie may engage the lining 12 of the tie, to hold the latter in place.

Since the splice includes the relatively rigid reinforcements 3 which are permanent 60 and securely attached to the ends of the strips 2, the strips 2 cannot roll up, nor can the ends of the tie, adjacent the reinforcements 3 roll up. By employing the reinforcements 3 as above pointed out, it is possible to make the strips 2 of exactly the same length, and the reinforcements may be assembled rapidly with the strips 2, in a machine, it being possible to turn out the complete splice, as an article of manufacture, 70 without sewing.

Having thus described the invention, what is claimed is:—

1. A necktie splice comprising a body member including a pair of strips disposed 75 edge to edge; and rigid transverse double-walled reinforcements clamped on the ends of the body member.

2. A necktie splice constructed in accordance with claim 1, and further characterized by the fact that the walls of the reinforcements are provided with projections which engage the body member.

3. A necktie splice constructed in accordance with claim 1, and further characterized by the fact that the outer corners of the reinforcements are beveled.

In testimony that I claim the foregoing as my own I have hereto affixed my signature in the presence of two witnesses.

WILLIAM WRIGHT CLIMENSON.
